UNITED STATES PATENT OFFICE.

JOHN N. WHITEHOUSE, OF NEWARK, NEW JERSEY.

DESIGN FOR A BUTTON.

46,465.

Specification for Design.

Patented Sept. 22, 1914.

Application filed July 11, 1914. Serial No. 850,509. Term of patent 3½ years.

To all whom it may concern:

Be it known that I, JOHN N. WHITEHOUSE, a citizen of the United States, residing at Newark, in the county of Essex and State of New Jersey, have invented a new, original, and ornamental Design for Buttons, of which the following is a specification, reference being had to the accompanying drawing, forming part thereof.

In the drawing: Figure 1 is a plan view of a button showing my invention; and Fig. 2 is an elevation of the same.

The unshaded portions of the button head represent transparent or translucent por-

tions thereof, while the shaded portions represent non-transparent or non-translucent portions. The button head is hollow, and the bottom wall thereof, which shows through the transparent or translucent portions, is given some light color, or it may be white.

I claim:

The ornamental design for a button, as shown and described.

JOHN N. WHITEHOUSE.

Witnesses:

HELEN V. FITZPATRICK,
MARY H. LEWIS.
